UNITED STATES PATENT OFFICE.

THOMAS SWOGER, OF WILKINSBURG, PENNSYLVANIA.

FOLDING PIANO.

1,119,054.

Specification of Letters Patent.

Patented Dec. 1, 1914.

Application filed April 9, 1914. Serial No. 830,760.

To all whom it may concern:

Be it known that I, THOMAS SWOGER, a citizen of the United States, residing at Wilkinsburg, in the county of Allegheny and State of Pennsylvania, have invented certain new and useful Improvements in Folding Pianos; and I do declare the following to be a full, clear, and exact description of the invention, such as will enable others skilled in the art to which it appertains to make and use the same.

This invention relates to improvements in pianos and has for its primary object to provide an upright piano so constructed as to allow the key board to be swung into the interior of the case and also having retractable supporting feet, these provisions being made for the purpose of diminishing the size of the instrument for the purpose of transportation or storage.

In carrying out the above end, it also becomes expedient to so mount the pedals as to allow them to be moved into the interior of the casing.

A secondary object of the invention is therefore to provide simple and efficient means whereby this operation may be performed without appreciable alteration to the parts operated thereby.

Still further objects of the invention are to provide means whereby the entire key board may be removed from the casing for repairing or cleaning and to provide simple and efficient means for locking the feet in extended or retracted position.

With these and other objects in view, the invention resides in certain novel features of construction and combination herein described and claimed and shown in the drawings wherein:

Figure 1 is a front elevation partly in section, with the parts in position for use; Fig. 2 is a horizontal section taken substantially upon the line 2—2 of Fig. 3; Fig. 3 is a vertical section on the line 3—3 of Fig. 1; Fig. 4 is a detail horizontal section taken on the line 4—4 of Fig. 3; Fig. 5 is a detail vertical section on the line 5—5 of Fig. 4; and Fig. 6 is a detail perspective view of portion 50 of the key board, looking from the under side thereof and showing more particularly the location of one of the fastening hooks. Fig. 7 is a detail perspective view of a portion of the case showing more particularly 55 one of the bearings for supporting the key board.

In the accompanying drawings, I have shown my improved piano casing as comprising substantially rectangular end walls 1 connected by the usual hinged top 2 and solid base board 3, the sound board B constituting the entire rear side of the casing as is usual with devices of this character. The strings S, mechanism for operating the hammers H, the keys K and the pedals P are of common construction and need no alteration in constructing the instrument in accordance with the following description.

The keys K are pivotally mounted in the usual manner upon the key board 1' which latter is provided with the usual end boards or cheeks 2' and with a pair of laterally projecting bearing studs 3' at its rear corners. The studs 3' are revolvably seated in curved bearing seats 4 which are formed in the upper sides of transverse blocks 5, the latter being rigidly secured to the inner sides of the end walls 1 and forming a reinforcement therefor and also constituting means to which certain of the finishing strips 6 are attached. The front ends of the blocks 5 are provided with inwardly extending recesses 7 in which upright pins 7 are anchored, said pins and notches coacting with the laterally swinging hooks 8 which are pivotally connected to the under side of the key board 1' near its opposite ends.

When the key board 1' is swung outwardly and the hooks 8 so positioned as to retain the same in this position, the rear ends of the keys K, carrying the usual capstan screws are disposed beneath the parts of the hammer operating mechanism with which they coact. When however, it becomes necessary to fold the key board, the hooks 8 are unfastened whereupon the entire board may be swung around its pivot studs 3', into the interior of the case. During this downward movement of the board 1', the capstan screws move away from the portions of the action with which they co-operate thus preventing any injury whatever thereto.

I have described the studs 3 as being mounted in the bearing notches 4 but it becomes necessary to provide means for removably retaining said studs in the notches, said means being here shown as consisting of a pair of pivot latches or buttons 9 which are carried by the end walls 1 and are adapted to have their lower ends swung

into engagement with the upper surfaces of the studs 3. When for any reason, it becomes necessary to remove the entire key board, the buttons may be swung aside 5 whereupon the studs 3' may be lifted out of the seats 4 thus leaving the entire key board and the keys free to be removed.

The front of the piano, above the key board, may be covered and ornamented in 10 any suitable manner and preferably comprises the usual panel P' which is adapted to swing outwardly and which usually carries the music rest, the keys K are likewise provided with a hinged cover 10 which latter is preferably carried by a longitudinal 15 strip 11 which is secured at its opposite ends to the cheeks 2', said strip overlying the keys and preventing dislocation thereof. It will be understood that the cover 10 folds inwardly with the key board.

The portion of the casing, below the key board, is closed by a removable panel 12 which carries an attaching bracket 13 on its inner side while its upper edge may be supported in position by any suitable means 25 such as spring catches 14 which is carried by the lower side of the key board 1 and is adapted to engage the outer surface of said panel when the key board is swung outwardly. The bracket 13 is adapted to engage the upper edge of a longitudinal strip or flange 15 which rises from the base board 3 of the casing, said strip 15 being provided with a number of openings, located near its center, through which the pedals P project and with openings 16 near its opposite ends, through which retractable bars 17 which carry depending feet 18 on their forward ends, are adapted to slide, the rear ends of 30 said bars being slidably engaged with guides 19 which are carried rigidly by the base board 3 and are provided with set screws 40 by means of which the bars 17 may be locked in either projected or retracted position.

As hereinbefore suggested, I provide means whereby the pedals P may be retracted when the remainder of the parts are in folded or retracted position. For this 50 purpose, I have provided a plate 21, preferably of wood, which overlies the central portion of the base board 3 and carries the pivots 22 of said pedals. The central portion of the plate 21 is provided with a transverse slot 23 through which projects an upright stud 24, the latter rising rigidly from said base board and receiving a thumb nut 25 on its upper end. By this construction, when the thumb nut 25 is loosened, the 55 plate 21 and the pedals P may be moved inwardly for obvious reasons. During this inward movement of the pedals, it becomes expedient to provide means for allowing the usual links R, employed for regulating the 60 sound of the instrument to remain in a

rigid position. For this purpose I have provided said links with stops R' on their lower ends, and have slotted pedals P as at 65 for the purpose of allowing the same to move upon the links R above the stops R'. Thus it will be seen that inward and outward movement of the pedals is allowed and yet the rods may assume their normal positions and may be readily operated when necessary.

From the above description, it will be seen that no appreciable amount of alteration need be made to any of the standard parts of a piano for the purpose of constructing the same in accordance with my 75 invention.

It will further be seen that by carrying out the operation above described, the key board, the pedals and the supporting feet may all be retracted so as to appreciably 80 diminish the size of the instrument, thus allowing the same to be moved through narrow doors, windows, and halls, or to be stored in approximately two-thirds the space 85 which would ordinarily be required.

I have described no ornamentation whatever between the key board and the bars 17 but it is to be understood that I intend, under the scope of the appended claims, to ornament the same in any manner which I 90 may deem appropriate.

I have described my invention with considerable minuteness and have stated certain specific forms of construction by means of which the idea may be effectually carried 100 out. I do not wish however to be limited to details of construction, arrangement of parts or other minor details other than as amplified in the appended claims.

Having thus described my invention, what 105 I claim as new and desire to secure by Letters Patent is:

1. A piano including an upright rectangular case, piano actions permanently mounted in the upper rear portion thereof, a key board pivoted beneath the actions to be swung downwardly within the casing or upwardly to normal position, transverse guides on the base of the case, the case having openings registering with said guides, transverse bars slidable in the guides and openings, means for locking the bars in extended or retracted position, and retractable 110 pedals adapted to slide into the interior of the case.

2. A piano including an upright rectangular case, piano actions permanently mounted in the upper rear portion thereof, a key board pivoted beneath the actions to be swung downwardly within the case or upwardly to a horizontal position, retractable supporting feet adapted to slide into the lower portion of the case, the front of said case having a centrally located opening near its lower end, a member mounted for lateral 115 120 125

sliding movement upon the base of the case, 5
pedals pivoted to said member and adapted
to slide through the opening, and means for
locking said member in adjusted position,
said pedals being adapted to operate the
sound damper.

3. A piano including an upright rectangular case, piano actions permanently mounted in the upper rear portion thereof, a key 10 board pivoted beneath the actions to be swung downwardly within the case or upwardly to a horizontal position, retractable supporting feet adapted to slide into the lower portion of the case, the front of said 15 case having a centrally located opening near

its lower end, a transversely slotted pivot plate overlying the base of the case, a threaded stud rising from said base through the slot, a nut on said stud, pedals pivoted to said plate and slideable through said opening, said pedals being adapted to operate the sound damper. 20

In testimony whereof I have hereunto set my hand in presence of two subscribing witnesses.

THOMAS SWOGER.
